UNITED STATES PATENT OFFICE.

BENJAMIN F. MAYO, OF SALEM, MASSACHUSETTS, ASSIGNOR TO THE MCKAY SHOE MACHINERY COMPANY, OF PORTLAND, MAINE, AND BOSTON, MASSACHUSETTS.

DESIGN FOR A PROTECTIVE SLUG.

SPECIFICATION forming part of Design No. 30,839, dated May 23, 1899.

Application filed April 26, 1899. Serial No. 714,594. Term of patent 14 years.

To all whom it may concern:

Be it known that I, BENJAMIN F. MAYO, a citizen of the United States, residing at Salem, in the county of Essex and Commonwealth of

5 Massachusetts, have invented and produced a new and original Design for a Protective Slug, of which the following is a specification.

Figure 1 is an end view of a protective slug, illustrating my design; and Fig. 2 is an elevation thereof viewed from the open end of the wings.

The leading feature of my design for a protective slug consists of an elongated body bent transversely to present a spear-shaped

5 contour with an open end.

The protective slug comprises an elongated body bent at *a* to form sides *b c*, incurved to

the ends *d e*, said wings being slightly separated, leaving a spear-shaped contour with an open space opposite the bend *a* or point of 20 the spear.

Having fully described my design, what I claim, and desire to secure by Letters Patent, is—

The design for a protective slug, substantially as herein shown and described.

In testimony whereof I have signed my name to this specification in the presence of two subscribing witnesses.

BENJAMIN F. MAYO.

Witnesses:

GEO. W. GREGORY,
MABEL PARTELOW.
